152,642, Nov. 15, 1961. This application Aug. 2,
1966, Ser. No. 569,754
5 Claims. (Cl. 260—404.5)

This application is a continuation of Ser. No. 152,642 filed Nov. 15, 1961.

This invention relates to improved mineral oil compositions, more particularly to certain additives which improve thermal stability of hydrocarbon liquids, especially jet engine fuels.

Some jet airplane systems are now designed to employ fuel stored in the plane as a heat sink to absorb heat generated in operation of the aircraft. The fuel may be heated in the tanks of the plane to high temperatures in the magnitude of 400–500° F. before it is ultimately consumed. Some jet fuels are unstable at these high temperatures. They deteriorate to form sludge which may clog fuel lines, filters and heat exchangers and may form harmful deposits in the engine.

A particular object of this invention is to provide jet engine fuels stabilized with certain additives that inhibit sludge formation at elevated temperatures. More generally an object is to provide certain additives for stabilizing liquid hydrocarbon fuels against deterioration at high temperatures. Another object is to provide new compounds useful as thermal stabilizers for hydrocarbon fuels, especially for jet engine fuels. The group of compounds which we have found suitable as additives for stabilizing jet fuels against high-temperature deterioration consists of certain N-acyl sarcosines and certain amide and diamide compounds which may be obtained by condensation of N-acyl sarcosines with certain amines and polyamines.

The N-acyl sarcosines which are effective stabilizers are those having the general formula:

wherein R represents an alkyl radical or alkenyl radical containing not less than 8 nor more than 18 carbon atoms. Specific examples of such compounds are N-pelargonyl sarcosine, N-lauroyl sarcosine, N-oleoyl sarcosine, and N-stearoyl sarcosine. N-oleoyl sarcosine is especially preferred. These compounds are available commercially.

Other compounds suitable for thermal stabilizers are amide derivatives of N-acyl sarcosines which may be obtained by condensation of one mole of an N-acyl sarcosine with one mole of a monoamine or a polyamine in which only one amino group has available hydrogen. These amide derivatives are represented by the general formula:

wherein R is the same as R defined above, R' represents a hydrogen atom or alkyl radical and R'' represents an alkyl, alkenyl, or alkylamino alkyl radical. In preferred embodiments, the total number of carbon atoms in R' and R'' does not exceed 24.

Preferred amines for preparing these derivatives may be primary alkyl amines, secondary dialkyl amines, or dialkyl amino alkyl amines. Examples of some typical amines that may be used for preparing these amide derivatives are methyl amine, dimethylamine, diethylamine, and dimethylaminopropylamine. Mixtures of amines of the type indicated are suitable for this purpose, for instance, a mixture of alkyl amines known as Primene

2

81-R. This is essentially a mixture of tertiary alkyl, primary amines in which the amino group is attached to a tertiary carbon atom of an alkyl group containing 18 to 24 carbon atoms per molecule. The condensation product 5 will be a mixture of N-acyl sarcosine amides having the general formula above.

The following example illustrates a typical method for making the monoamide derivative of the invention.

Example 1

Equimolar amounts of N-oleoyl sarcosine and Primene 81-R were mixed in a reaction flask equipped with a reflux condenser and a Dean-Stark trap. The mixture is then heated and refluxed at a temperature of 190–260° F. 15 until no further water collects in the trap. A slightly viscous, light-brown product remains in the flask. An acid number (ASTM D-974) of only 17 indicates the product is essentially the amide condensation product.

Preferred among the stabilizing compounds provided 20 according to this invention are the diamide derivatives of N-acyl sarcosines obtained by condensation of two moles of a N-acyl sarcosine with one mole of a polyalkylene-amine. These diamide derivatives are represented by the general formula:

wherein R represents an alkyl or alkenyl radical containing not less than 8 nor more than 18 carbon atoms, and 30 n is 1–4.

Typical of the polyalkyleneamines which may be used as reactants to produce these diamide derivatives are ethylenediamine, diethylenetriamine, triethylenetetramine, and tetraethylene pentamine. Following is an example 35 illustrating a preferred method for preparing the diamide derivative.

Example 2

31.8 g. of N-oleoyl sarcosine and 8.4 g. of tetraethylene 40 pentamine (2:1 molar ratio) are mixed in a reaction flask equipped as in Example 1. The mixture is heated and refluxed at 178–250° F. until no further water collects in the trap. The residue is a viscous brown liquid. Its acid number is only 1.9, indicating that the residue is 45 essentially the diamide condensation product.

Ability of the stabilizer compounds of the invention to improve thermal stability of jet fuels was tested in the CFR (Cooperative Fuel Research) Fuel Coker.

The test is described in a paper by Crompton et al. 50 titled, "Thermal Stability, a New Frontier for Jet Fuel," and published in the Proceedings of the S. A. E. Summer Meeting in 1955. Instructions for operating the CFR Fuel Coker are in Manual No. 3 of Coordinating Research Council, Inc. Essentially the test is as follows:

55 Jet fuel is pumped at 150 p.s.i. and at a flow rate of 4–6 pounds per hour through a preheater, thence through a furnace where the fuel passes through a 20 micron, sintered stainless steel filter. In the preheater the fuel is heated to 300–400° F. and in the furnace to 400–500° F. 60 Degradation products are deposited in the preheater and are also trapped on the filter where they eventually cause a pressure drop, which is measured across the filter by a manometer. The test continues until a pressure drop of 25 in. Hg is observed on the manometer, or until expiration of 300 minutes, whichever occurs first. Fuel stability is expressed in "goodness" units, an empirical function of observed pressure drop and test time. The scale of goodness units ranges from 0 for immediate clogging to 900 for no observed pressure drop within 300 minutes. At the end of the test the apparatus is disassembled and the preheater parts which were in contact with the fuel are examined for deposited material.

UNITED STATES PATENT OFFICE
CERTIFICATE OF CORRECTION

Patent No. 3,324,155

June 6, 1967

John W. Thompson et al.

It is hereby certified that error appears in the above numbered patent requiring correction and that the said Letters Patent should read as corrected below.

In the heading to the printed specification, lines 3 and 4, for "John W. Thompson and James C. Ownby, both of P. O. Box 511, Kingsport, Tenn. 37662" read -- John W. Thompson and James C. Ownby, both of Kingsport, Tenn., assignors to Eastman Kodak Company, Rochester, N. Y., a corporation of New Jersey --.

Signed and sealed this 17th day of December 1968.
